UNITED STATES PATENT OFFICE.

CHARLES FAYER, OF NEW YORK, N. Y., ASSIGNOR TO WAPPLER ELECTRIC CO., INC.,
A CORPORATION OF NEW YORK.

CURRENT REGULATOR FOR X-RAY SYSTEMS.

Application filed April 2, 1918. Serial No. 226,169.

To all whom it may concern:

Be it known that I, CHARLES FAYER, a citizen of the United States, residing in the city of New York, borough of Bronx, in the county of Bronx and State of New York, have invented certain new and useful Improvements in Current Regulators for X-Ray Systems, of which the following is a full, clear, and exact description.

10 My invention relates to current regulators for X-ray systems, and more particularly such systems in which the X-ray tube is of the so-called Coolidge type—that is, a tube in which ionization is promoted by means of a cathode heated to incandescence.

In such a system it is customary to energize the X-ray tube by currents from a high tension transformer of large capacity and known as the main transformer and to 20 heat the cathode of the tube by currents from a low-tension transformer of smaller capacity—both transformers, however, being energized by currents drawn from a single source of supply, say a pair of alternating 25 current mains.

When, therefore, the X-ray tube is thrown into action there is likely to be a substantial drop in the voltage of these currents and consequently a drop in the temperature of 30 the heating filament, so that the current passing through the tube is in practice much less than would be warranted by the carrying capacity of the tube.

I seek to prevent this evil, by preventing 35 the drop in the temperature of the filament.

I find that under ordinary conditions of 40 operation, the number of milliamperes passing through the X-ray tube is nearly constant if the heat of the cathode is maintained constant, and that as a consequence the number of milliamperes passing through 45 the tube may be maintained approximately constant by controlling the current used for heating the cathode. I also find that with my device the control of the current for heating the cathode may be rendered automatic.

50 By my invention, therefore, I seek to render practically constant the current discharge through the X-ray tube, independently of any variations in voltage to which the high-tension transformer may in practice be subjected.

55 In addition I render the system adjust-

able, so that the operator may, at will, vary, within reasonable limits, the degree of control exerted by the line voltage upon the flow of current through the X-ray tube.

Reference is made to the accompanying 60 drawing forming a part of this specification, and in which like reference characters indicate like parts in all of the figures.

Figure 1 is a diagram of my system complete.

65 Figure 2 is a diagrammatic perspective, showing one form of the low-tension transformer and parts immediately associated therewith.

Figure 3 is a diagram of another form of 70 the low-tension transformer.

An X-ray tube is shown at 4, and is of the kind commonly known in this art as a Coolidge tube, being provided with a heating filament 5. The polarity of the tube is 75 indicated conventionally by plus and minus signs.

A transformer 6 is used for energizing the heating filament.

The X-ray tube is energized by currents 80 from a high-tension transformer 7, that is, the main transformer, these currents being acted upon by a rectifying device 8, which is here indicated by the legend "Rectifying device."

85 The mains are shown at 9, 10, and are energized by alternating current from a power-plant, not shown.

The transformer 6 has practically no 90 magnetic leakage, and is provided with a primary winding 11. A wire 12 leads from the main 10 to this winding. A wire 13 leads from the main 9 to a choke coil 14, and from the latter a wire 15 leads to the primary winding 11.

95 The transformer 6 has a secondary winding 16, and from this winding a wire 17 leads to the heating filament 5, which is the cathode of the X-ray tube. A wire 18 is connected to this filament and also to a wire 19, which leads to the secondary winding 16.

A wire 20 is connected to the wires 18 and 19, and to the rectifying device 8. A wire 21 leads from the rectifying device to the X-ray tube.

100 Two wires 22, 23 are connected to the rectifying device and also to a secondary winding 24 with which the high-tension transformer 7 is provided.

105 The main transformer 7 has a primary 110

winding 25, and to it is connected a wire 26, leading to a switch 27. Two wires 28, 29 extend from the mains 10, 9 to the switch 27. A wire 30 extends from the switch 27 to a winding 31, carried by a core 32. This core is made of soft iron, preferably laminated, and is used in connection with the transformer 6, relatively to which it is adjustable. From the winding 31 a wire 33 leads to the primary winding 25 of the high-tension transformer 7, and is thus in series with this last-mentioned primary winding.

The core 32 rests loosely upon the transformer 6, and is provided with an adjusting screw 34. The operator by merely turning this screw and thereby raising or lowering the adjacent end of the core 32 relatively to the transformer 6, can within reasonable limits control the electromagnetic relations of the transformer 6 and the core 32.

I designate the iron core 32, with its winding 31, as a compensator. When the compensator is in action, some of the magnetic flux generated in the core 32 tends to find a path through the closed core of the transformer 6.

The number of turns in the windings 11 and 31 are so apportioned, and the polarity of the core 32 relatively to that of the transformer 6 is so arranged, that the magnetic flux set up in the transformer by action of the primary winding 11 has little or no effect upon the core 32, yet the magnetic flux set up in the core 32 by action of the winding 31 may have a considerable effect upon the iron frame of the transformer. That is to say, the number of turns in the primary winding 11 (which is in series with the choke coil 14) is such that the magnetic flux set up by this winding is proportionate to the current energizing this winding, and hence proportionate to the current in the mains 9, 10; but the number of turns in the winding 31 is such that the magnetic flux set up by this last mentioned winding is always at a maximum, and thus practically constant, independently of variations in the current energizing the winding 11 or in the current in the mains 9, 10. In other words, the core 32 is maintained comparatively near its saturation point even when there is a considerable drop in the voltage of the line.

The polarity of the core 32 is so arranged relatively to that of the transformer 6, that the magnetic flux induced by the primary winding 11 and that induced by the compensator winding 31, both tend to pass in a common direction through the secondary winding 16. Thus, while owing to the alternating character of all currents employed, the polarity of both the transformer and the compensator is alternating, and as a

consequence the magnetic flux passing through the secondary winding 16 is likewise alternating, yet at any particular moment the magnetic flux passing through the winding 16 is due to the conjoint effect of the respective windings 11 and 31, which act alike in phase.

If, now, by turning of the screw 34, the position of the compensator be properly adjusted relatively to the transformer 6, the leakage of magnetic flux from the core 32 through the closed core of the transformer 6 is just enough to superpose, on the flux in the transformer core, so much energy as will tend to minimize the ultimate effect of a drop in the voltage of the primary winding 11. Thus the flux passing from the core 32 and finding its way through the secondary winding 16 is substantially constant. The result is that the temperature of the cathode 5, and consequently the current passing through the X-ray tube, is also substantially constant.

In some instances I prefer to use, as the low tension transformer, the device 6* shown in Figure 3. Here I place a winding 31* upon the closed core of the transformer, and provide a sliding contact 35 for varying the effective number of turns of this winding. The wires 30*, 33* are for the purpose of energizing the winding 31*, and used in the same manner as the wires 30, 33 above described.

The operator by actuating the sliding contact 35 can increase or diminish the number of effective turns of the winding 31*, and by so doing can regulate the quantity of magnetic flux generated by the winding 31*. Thus the winding 31* and its sliding contact 35 are an equivalent for the winding 31 and its adjustable core 32, and together constitute a compensator as the term is used in the foregoing description.

In order to keep the cathode current substantially constant, it is desirable that the flux developed by the winding 31 be very large with respect to that developed by the winding 11.

The switch 27 being closed, the high-tension transformer 7 and the low-tension transformer 6 are energized. Currents induced in the secondary winding 24 pass through the wires 22, 23 to the rectifying device 8, and thence the rectified currents pass through the wires 20, 21 to the X-ray tube 4 through which they pass in a unitary direction, indicated by the signs plus and minus. The rectifying device 8 is not in all instances essential, as a Coolidge tube is itself a rectifier under most conditions normally obtaining in practice.

Currents induced in the secondary winding 16 pass through the wire 17, the cathode 5 and wires 18 and 19, thus heating the cathode 5.

It will be noted that the winding 31, carried by the core 32, is in series with the primary winding 25, and as the currents passing through this winding 25 are very powerful, the core 32 is highly magnetized, so that its magnetic flux exerts a considerable influence upon the transformer 6 whenever the tube is operated.

The current supplied to the heating circuit by the low-tension transformer 6 is thus maintained substantially constant, and as a consequence the temperature of the cathode remains fixed, and the current through the X-ray tube is maintained substantially constant.

To obtain the best results the operator can make proper adjustment as above described, and this may be done with either of the two forms of compensator shown respectively in Figures 2 and 3.

I do not limit myself to the precise mech-

anism shown, as variations therefrom can be made within the scope of my claim.

I claim:—

The combination of an X-ray tube provided with a cathode to be heated, a transformer connected with said cathode in order to heat said cathode by supplying currents thereto, a transformer connected with said X-ray tube for the purpose of exciting the latter, a circuit connected with said last mentioned transformer in order to energize said last mentioned transformer, and electromagnetic mechanism energized by said circuit, said electromagnetic mechanism being so positioned and arranged relatively to said first mentioned transformer that the magnetic flux of said electromagnetic mechanism reaches directly said first mentioned transformer, and modifies the magnetic flux thereof.

CHARLES FAYER.
